TOY AIRPLANE

Ada M. Hoffman, Los Angeles, Calif.

Application August 22, 1958, Serial No. 52,336

Term of patent 7 years

(Cl. D34—15)

Fig. 1 is a top plan view of a toy airplane, showing my new design;

Fig. 2 is a side view;

Fig. 3 is a front view; and

Fig. 4 is a rear end view.

I claim:

The ornamental design for a toy airplane, substantially as shown.
